UNITED STATES PATENT OFFICE.

FRANK C. ANDERSON, OF CINCINNATI, OHIO, ASSIGNOR TO THE AMERICAN VALVE AND METER COMPANY, OF CINCINNATI, OHIO, A CORPORATION OF OHIO.

LOCKING DEVICE FOR INTERLOCKING SWITCH STANDS.

Application filed September 11, 1924. Serial No. 737,149.

To all whom it may concern:

Be it known that I, FRANK C. ANDERSON, a citizen of the United States, residing at Cincinnati, in the county of Hamilton and 5 State of Ohio, have invented certain new and useful Improvements in Locking Devices for Interlocking Switch Stands, of which the following is a specification.

My invention relates to switch-stands, and 10 more especially to switch-stands of the ground-throw type similar to that disclosed and claimed in my prior Patent No. 1,234,522, dated July 24, 1917, in which is a provision for automatically latching the switch-throwing lever and for releasing the latch upon manual release of the interlocking mechanism, the latter being engaged automatically by spring pressure upon the switch being completely closed.

20 The object of my present invention is to lock the interlocking mechanism directly by a manually applied lock, so that, although the latch may operate independently of the interlocking mechanism for latching the lever or for releasing the same, the interlocking mechanism will remain safely locked should the switch-stand proper and its latch, which heretofore has received the manually applied lock, be torn away from the interlocking mechanism in an accident such as 25 may result from the stand being struck by a projecting object on a passing train, or by a vehicle or the like thrown against the stand by a train. Other objects will appear 30 in the course of the ensuing description.

I attain these objects by the device illustrated, for example, in the accompanying drawing, in which—

Figure 1 is a general perspective view 40 of part of a switch and a switch-stand connected thereto, embodying my invention;

Fig. 2 is a partial plan view, enlarged, of the interlocking mechanism including my improved locking device;

45 Fig. 3 is a partial side elevation of the same.

Fig. 4 is a vertical longitudinal section of the same; and

50 Fig. 5 is a partial front elevation of the same, together with the latch, and including the switch-throwing lever in cross-section.

The switch-stand 1 has the upright target shaft 2 with bearings in the casing 3, which,

as is well known in the art, contains gearing 55 or the like which transmits motion from the switch-throwing lever 4 thrown in a vertical plane parallel with the track; the lower end of the target shaft having a crank connected with the point rails, one of which rails 5 is 60 shown, by the connecting rod 6 and the bar 7, which is understood to extend across and connect to the opposite point rail, not shown.

At either end of its throw the lever 4 is received in a respective latch 8 which comprises a member 9 swinging on a pivot 10 to engage its nose 11 over the lever 4 after being pushed aside by the down coming lever 4 engaging a slanting top 12 of this latch member 9. The bottom of this member 70 9 has an extension 13 which, when the interlocking mechanism is not used, forms a treadle engaged by the switchman's foot to open the latch; and the top of the latch frame has an ear 14 which, under such circumstances receives the bow of a pad-lock to prevent opening of the latch. Also, as heretofore used with the interlocking mechanism as shown in my prior patent mentioned above, this has been the means for locking 80 the switch manually.

The interlocking housing 15 is set into a gain in one of the head blocks that support the stand, with a stirrup 16 projecting outside the head block and having sliding 85 through it the interlocking bar 17 with an opening through which the plunger 18, sliding in the housing 15, is adapted to extend, as shown, when the opening of the bar 17 registers with the openings in the stirrup 16 90 that guide the plunger. This interlocking bar 17 extends under the stock rail and has its end connected to a deflecting guard plate 19 bolted to the end of the point rail 5, so that there cannot be registry of the openings 95 to admit the plunger 18 unless the point rail 5 is safely against the stock rail. As shown in Fig. 4, and also in my above mentioned patent, the plunger 18 enters the registering openings under pressure of a spring 18' 100 in the housing, and is manually withdrawn by engagement of an arm 18 in the housing swinging with fulcrum bearings in the sides of the housing. In that patent, the fulcrum extends outside the casing, with a treadle fixed on it at one side of the casing, depressed by the switchman's foot and thereby withdrawing the plunger; and this treadle 105

engages the treadle extension 13 of the adjacent latch 8 to open the latch concurrently with releasing of the interlocking mechanism.

5 In my present invention, instead of a treadle on this part of the interlocking mechanism, there are levers swinging with the inner arm 18'', each having two arms 20 and 21, at opposite sides of the housing 15. The 10 arms 20 extend forward, or toward the end of the mechanism receiving the interlocking bar, and one or the other arm 20 is adapted to engage the latch extension 13 as did the treadle in my prior device; while the other 15 arms 21 extend back past the other or rear end of the housing. The forward arms 20 are provided at both sides in order that the same interlocking mechanism may be used with a latch 8 placed at one side or the other 20 of the mechanism, as is incident to use of the stand at either the right or left side of the track, or for either left-hand or right-hand turnouts.

In one or the other of these installations 25 one or the other arm 20 would operate, with the one at the opposite side idly swinging therewith.

In my present invention I provide the top of the interlocking housing or casing 15 30 with an upstanding lug 22 just back of the bearing for the fulcrum of the arms 20 and 21, and having an ear 23 projecting forward over this bearing. Also, the top of the housing has, just forward from this bearing, the 35 upstanding ears 24. The locking yoke or hasp 25 comprises a hood 26 fitting down over the lug 22 with its front side provided with a slot 27 through which projects the ear 23 of the lug 22 when the hood is down 40 on the lug. Some distance forward from this hood 26 the yoke 25 has a hub fitting between the ears 24 of the housing top, and a fulcrum pin 28 extends through the ears and the hub. From this hub, the treadle 45 29 extends forward and slightly upward, forming the front end of the yoke or hasp 25. From the rear of the hood 26 there is an extension 30 having a depending head 31 at the rear end of the housing 15. A round 50 bar 32 has its ends fixed in the respective rear arms 21 of the side levers, near the rear ends of these arms, and extends through a slot 33 in the head 31 of the extension 30; thus forming a connecting extension from 55 the yoke or hasp 25 to the side levers. The slot 33 permits the relative movement of the hasp 25 and the levers, incident to the different locations of the fulcrums of the two elements; and when the treadle 29 is 60 depressed by the foot of the switchman, the rear arms 21 are raised, rotating the interlock-operating element of which these arms are unitary parts, withdrawing the plunger 18 from the bar 17. This swings the forward arms 20 of this element down, and the 65

one engaging the extension 13 of the latch 8 depresses this treadle, withdrawing the nose 11 of the latch from the lever 4. Thus, the plunger 18 releases the bar 17, and the latch 8 releases the switch-throwing lever 4, 70 so that the latter may be swung over, opening the switch by drawing the point rail away from the stock rail.

With the bow of a padlock 34 (Fig. 1) inserted in the ear 23, the yoke or hasp 25 75 is prevented from rising, and, by engagement of its extension bar 32 with the arms 21 it prevents rising of these arms as is necessary for withdrawal of the plunger 18 from the bar 17, even were the switch-stand, 80 including its latch 8, torn away. This would not be the case with my prior invention before mentioned, in which the lock was applied to the latch 8 and would be carried away with the latch. Thus, danger of withdrawal of the plunger in the absence of the latch, pending repair, is avoided.

With my present invention, the switch-stand is manually locked through the medium of the plunger and interlocking bar, 90 the point rail and the connecting rod, rather than by locking the switch-throwing lever directly by means of the latch. It is possible to swing the latch member 9 away from the lever 4, but with the interlocking plunger engaged, opening of the switch is prevented through the above means. The latch 8 retains its automatic reception of the lever 4 and holds the lever to prevent its vibration by the impact of traffic on the switch, 95 rails; but the actual locking is effected by the more directly connected interlocking mechanism. As the pad-lock cannot be inserted into the ear 23 until the hasp or yoke 25 is entirely down and the plunger 18 is 100 in the opening of the bar 17, and as this opening cannot receive the plunger unless the point rail is safely against the stock rail, it is impossible to lock the switch with an obstruction between the stock rail and point rail such as would hold the rails apart 105 far enough to endanger traffic. Thus the function of my prior invention is fully performed, and in addition, this insurance of safe relation of the rails is maintained even in the absence of the switch-stand proper, due to an accident of the kind before alluded to. In the direct locking of the switch rails through the interlocking device, independently of the switch-throwing means, my present invention is similar 110 to that disclosed and claimed in my co-pending application, Serial No. 21,057, filed 115 April 6, 1925.

Modifications of my invention may occur, 125 in conjunction with modified switch-throwing or interlocking mechanism, or with that herein exemplified; and I do not wish to be understood as being limited to the precise disclosure herein, but having fully described 130

my invention, what I claim as new and desire to secure by Letters Patent is:

1. In a switch-stand comprising a switch-throwing element and a latch for said element, interlocking mechanism for said switch-stand, manipulating means for concurrently disengaging said latch and said mechanism, and means for locking said manipulating means.
2. In a switch-stand comprising a switch-throwing element and a latch automatically retentively receiving said element, interlocking mechanism for said switch-stand, manipulating means engageable with said latch for concurrently disengaging said latch and said mechanism but leaving said latch free for reception of said switch-throwing element, and means for locking said manipulating means.
3. In a switch-stand, in combination with the switch-throwing element thereof, a latch for said element having an extension depressible for opening the latch, and interlocking mechanism having depressing engagement with said extension, a treadle for operating said mechanism, and means for locking said treadle.
4. In a switch-stand, in combination with the switch-throwing element thereof and a latch for said element and interlocking mechanism for said switch-stand comprising a housing with an upstanding ear and having operative relation to said latch, means movably mounted on said housing and having an opening through which said ear projects to receive part of a lock for manually locking said mechanism.
5. In a switch-stand, in combination with the switch-throwing element thereof and a latch for said element, interlocking mechanism comprising a housing with an upstanding ear and having an arm swinging at one side of said housing to engage with said latch, and a locking member swinging on said housing having an extension operatively related to said arm and having an aperture through which said ear extends to receive part of a lock for manually locking said mechanism.
6. In a switch-stand, in combination with the switch-throwing element thereof and a latch for said element, interlocking mechanism comprising a housing and having an arm swinging at one side of said housing to engage with said latch, and means on said housing for locking said arm.
7. In a switch-stand, in combination with the switch-throwing element thereof and a latch for said element, interlocking mechanism comprising a housing and having arms swinging at opposite sides of said housing, one or the other arm being adapted to engage with said latch accordingly as said latch is at one or the other side of said housing, and means on said housing for locking said arms.
8. In a switch-stand, in combination with the switch-throwing element thereof and a latch for said element, interlocking mechanism comprising a housing and having a two-armed lever swinging at one side of said housing, an arm of which is adapted to engage with said latch, and a locking member swinging on said housing having an extension operatively related to the other arm of said lever, said locking member being adapted to be manually locked against operative movement.
9. In a switch-stand, in combination with the switch-throwing element thereof and a latch for said element, interlocking mechanism comprising a housing and having levers swinging at opposite sides of said housing, each lever having two arms, and a locking member swinging on said housing, adapted to be locked against operative movement and having operative relation to one arm of each lever, the other arm of one lever or the other being adapted to engage with said latch, accordingly as the latch is on one or the other side of said housing.
10. A locking member for switch-interlocking mechanism comprising an apertured middle part, means for pivoting said member near one end of said middle part, means for operatively connecting said member to the mechanism, near the other end of said middle part, and an extension on said member adapted to be engaged for swinging said member.
11. A housing for switch-interlocking mechanism having pivoting means and a locking ear on its top, and a locking member having a hood part fitting around said ear with an aperture through which said ear extends to receive a lock, means for operatively connecting said locking member to the mechanism, means for pivoting said member to said housing, and means on said member adapted to be engaged for swinging said member on said housing.

FRANK C. ANDERSON.
